UNITED STATES PATENT OFFICE.

WELLINGTON I. CLEMENTS, OF NORFOLK, VIRGINIA.

COMBINED ASH AND DUST PAN.

Application filed March 6, 1926. Serial No. 92,982.

This invention relates to ash pans, and has for one of its objects the provision of a novel, simple and inexpensive device of this character from which the ashes can be easily and quickly discharged into a box, barrel or other suitable receptacle without creating dust, the invention comprehending an ash pan having a bottom that can be gradually moved from closed to opened position so as to permit the ashes to be discharged into the receptacle in a manner to prevent the creation of dust.

A further object of the invention is the provision of an ash pan with a cover adapted to prevent the scattering of the ashes while carrying the ash pan from the stove to the ash receptacle and adapted to prevent the scattering the ashes from the upper side of the ash pan while discharging the ashes into the receptacle, the cover being freely removable from the ash pan to permit of its being used as a dust pan.

With the foregoing and other objects in view, the invention consists of the novel construction, combination and arrangement of parts hereinafter fully described, and claimed, and illustrated in the accompanying drawing, wherein:

Figure 1 is a top plan view of an ash pan constructed in accordance with my invention,

Figure 2 is a view in rear elevation of the ash pan;

Figure 3 is a view in side elevation of the ash pan;

Figure 4 is a transverse sectional view taken on the plane indicated by the line 4-4 of Figure 1.

Figure 5 is a longitudinal sectional view of the ash pan provided with a combined cover and dust pan, and

Figure 6 is a detail sectional view taken on the plane indicated by the line 6-6 of Figure 3.

Corresponding and like parts are referred to in the following description, and designated in the several views of the accompanying drawing, by similar reference characters.

The ash pan comprises lateral sides 1, a front side 2, a rear side 3, and a bottom 4. The bottom 4 is connected at its front edge to the lower edge of the front side 2 by means of a hinge 5. When in closed position, the bottom 4 lies in full abutting con-

tact with the lower edges of the sides 1-3, and any suitable means may be employed to releasably secure the bottom in closed position. This means may, as shown, consist of an eye 6 secured to the bottom 4 and a hook 7 secured to the front side 2. To permit of the application of this means at the outer side of an ash pan, the bottom 4 is made to project slightly beyond the rear side 3, the eye 6 being secured to the upper side of the projecting portion of the bottom and the hook 7 pivoted to the outer side of the front side. The bottom 4 is provided at its lateral edges with upstanding flanges 8 which contact with the outer surfaces of the sides 1 to prevent the ashes from working out of the ash pan between the lower edges of said sides and the bottom and to prevent the lateral spreading of the ashes while being discharged from the ash pan. A bail 9 is pivoted to the sides 1 as at 10, and is adapted when in position for use to occupy the full line position shown most clearly in Figures 1, 3 and 5. When the ash pan is in the ash pit of the stove, the bail 9 is adapted to occupy the folded position indicated by dotted lines in Figure 3. The bail 9 is pivoted to the ash pan rearwardly beyond the vertical transverse center of the latter. When the ash pan is supported by the bail 9, the tilting movement of the former is limited by spring stops 11 which are secured to the outer surfaces of the sides 1 and engage the bail. The stops 11 are also adapted to hold the bail 9 in position for use against casual movement into its folded position. A handle 12 is secured to the outer surface of the side 2 and provides means by which the ash pan can be inserted in and withdrawn from the ash pit of the stove. A cover 13 is removably positioned upon the upper side of the ash pan and is provided with lateral flanges 14 which contact with the outer surfaces of the sides 1 and a front flange 15 which contacts with the outer surface of the side 2. The cover 13 prevents the scattering of the ashes while carrying the ash pan from the stove to the ash receptacle and while discharging the ashes from the ash pan. The cover 13 is adapted, when not used in connection with the ash pan, to be employed as a dust pan, and to permit of its being employed for this purpose and to permit of its easy application to and removal from the ash pan, it

is provided at its front end with a handle 16.

In practice, when it is desired to dump the ashes accumulated therein, the ash pan is withdrawn from the ash pit of the stove by means of the handle 12. The cover 13 may be applied to the ash pan either before or after it has been withdrawn from the ash pit. The bail 9 is then swung into its upright position, and the ash pan is carried by the bail to the ash receptacle. The hook 7 is then withdrawn from engagement with the eye 6 to free the bottom 4 which latter part is then gradually lowered until all of the ashes have been discharged from the ash pan. After the discharge of the ashes, the bottom 4 is moved into and secured in closed position, and after the lowering of the bail 9 into its folded position and the removal of the cover 13, the ash pan is again placed in the ash pit of the stove.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. An ash pan comprising front, rear and lateral sides, a bottom hinged at its front end to the lower edge of the front and projecting beyond the rear, flanges extending upwardly from the lateral edges of the bottom and contacting with the outer faces of the lateral sides, and means carried by the projecting portion of the bottom and the rear to secure the bottom against casual movement.

2. An ash pan comprising front, rear and lateral sides, a bottom hinged at its front end to the lower edge of the front and projecting beyond the rear flanges extending upwardly from the lateral edges of the bottom and contacting with the outer surfaces of the lateral sides, means carried by the projecting portion of the bottom and the rear to secure the bottom against casual movement, a bail pivoted to the lateral sides rearwardly beyond the transverse vertical center of the pan, and stops secured to the lateral sides rearwardly beyond the pivots of the bail and adapted to be engaged by the bail when the latter is in position for use.

In testimony whereof I affix my signature,
WELLINGTON I. CLEMENTS.
